SIDETRACKING APPARATUS

Albert L. Eastham, Beaumont, Tex.

Application February 18, 1936. Serial No. 64,538

8 Claims. (Cl. 255—1)

This invention relates to a sidetracking apparatus and has particular relation to means for sidetracking a well for the purpose of drilling deeper. The invention has more particular relation to apparatus specially designed for milling a side opening or "window" in a pipe set in a well bore through which side opening subsequent drilling operations may be carried on for the purpose of drilling the well deeper.

10 In well drilling operations the well sometimes becomes obstructed by objects dropped or stuck in the bore which must be sidetracked; or the lower end of the bore becomes inclined or crooked and it may be necessary to sidetrack in order to straighten the bore. It is common practice in such cases, or in any other cases where it may be desirable to sidetrack, to locate a whipstock in the well and to employ a milling tool in cooperation with the whipstock to sidetrack the lower end of the bore. The invention herein described 15 comprises a novel type of sidetracking apparatus designed to be used in cooperation with the whipstock for the purpose of perforating the side wall of the pipe or casing in the well to form a "window" or opening through which subsequent drilling operations may be carried on.

A further object of the invention is to provide apparatus of this character which will securely maintain the whipstock against turning while carrying on the sidetracking operations, and which will also hold the milling cutter firmly against the casing or pipe to be perforated so as to efficiently carry on the perforating operation.

It is a further object of the invention to provide a sidetracking apparatus which includes a milling cutter and means whereby the cutter may be positively driven and guided.

It is a further object of the invention to provide apparatus of this character wherein the milling tool will be relieved of the weight of the operating string and will be automatically fed to the work without lowering the operating string during the sidetracking operation.

With the above and other objects in view, the invention has particular relation to certain novel features of construction, operation, and arrangement of parts, an example of which is given in this specification and illustrated in the accompanying drawings wherein:

50 Figure 1 shows a side view, partly in section, of the lower end of the sidetracking apparatus as the same is being lowered, with the whipstock attached, into the well, said view showing the well casing in section and showing also a 55 fragmentary view of the whipstock.

Figure 2 shows a side view, partly in section, of the upper portion of the sidetracking apparatus in the casing.

Figure 3 shows a vertical, sectional view taken at right angles to the views of the device shown 5 in Figures 1 and 2.

Figure 4 shows a side view of the complete sidetracking apparatus in operative position in the casing to be perforated.

Figure 5 shows an enlarged cross-sectional view 10 taken on the line 5—5 of Figure 3.

Figure 6 shows an enlarged cross-sectional view taken on the line 6—6 of Figure 3.

Figure 7 shows a cross-sectional view taken on the line 7—7 of Figure 1, and 15

Figure 8 shows a cross-sectional view taken on the line 8—8 of Figure 3.

Referring now more particularly to the drawings wherein like numerals of reference designate similar parts in each of the figures, the numeral 1 designates a casing set in a well bore and which is to be perforated, and the numeral 2 designates a conventional whipstock adapted to be set in the casing to be sidetracked.

As is well known to those familiar with the 25 art, the upper end of the whipstock tapers, forming the sloping face 3 which is arcuate in cross-sectional contour. This whipstock may be secured against downward movement at any desired point in the well by conventional means now 30 used for that purpose.

Referring now more particularly to the sidetracking apparatus forming the subject matter of the present invention, the numeral 4 designates a wedge-like anchor which, in the main, 35 is a solid body whose outer surface 5 is shaped to conform to the shape of and to fit closely against the inside of the pipe 1 and whose inner side 6 is shaped to conform substantially to the arcuate sloping face of the whipstock. The sides 40 5 and 6 converge or taper downwardly so that the anchor 4 will wedge between the sloping face 3 and the opposite side of the pipe 1. When in operative position, this anchor will prevent the whipstock 2 from turning during the milling operation, as will be more fully explained hereinafter.

The upper end of the anchor 4 has the socket 7 to receive the ball joint member 8 and also has a 45 transverse keyway 9. The joint member 8 is provided with an upstanding stem 10 whose upper end is formed with a head 11. A gland 12 surrounds the stem 10 and is screwed into the anchor 4 to retain the ball joint member 8 seated in the socket 50 55

7, and this gland flares upwardly to provide the necessary range of movement of the stem 10.

The lower end of the ball joint member 8 has a transverse keyway 13 which is aligned with the keyway 9 and a key 14 is inserted through said keyway to prevent the turning of the ball joint member 8 relative to the anchor 4, but to permit a swinging movement of the stem 10 in the plane of the keyway 9.

10 The numeral 15 designates an approximately cylindrical bar. A coupling 16 is threaded to the lower end of said bar and the lower end of said coupling is reduced inwardly to form a bearing 17 through which the spindle 18, carried by the head 11, works. A swivel nut 19 is located within the coupling 16 and is screwed on to the upper end of the spindle 18 whereby the bar 15 is connected to said spindle, but is rotatable relative thereto.

15 The numeral 20 designates an operating string 20 of pipe which extends to the ground surface and which is connected to the upper end of the bar 15 by means of the tubular coupling 21. The lower end of this coupling is enlarged, or bell-shaped, at 22, said enlarged portion being of slightly smaller 25 diameter than the inside diameter of the pipe 1 so as to ride against the inside of the pipe to prevent wabbling movement of the bar during operations.

20 Slidably mounted on the bar 15, but non-rotatable relative thereto, there is a suitable milling cutter, as 23, whose lower end is formed with the cutter blades or bits 24. The bar 15 has a deep groove 25 in one side thereof and extending longitudinally approximately from end to end thereof. Mounted in the upper and lower ends, respectively, of this groove are the bearing blocks 26, 27, which are suitably secured in place, and a screw shaft 28 is located in the groove 25 and has its ends mounted in bearings in the respective blocks 26, 27, said bearings being in alignment, but being 30 eccentric with respect to the axis of the bar 15. A nut 29 is fastened to the inside of the milling tool 23 and is fitted in the groove 25 and the said shaft 28 is threaded through the nut 29.

25 Fixed on the lower end of the shaft 28, there is the star wheel 30 which is housed within the coupling 16, and is located between the lower end of the bar 15 and the upper end of the spindle 18. Upstanding from the nut 19 and located at one 35 side of the coupling 16, there is the finger 31 arranged to be engaged by the star wheel 30 as the shaft 28 revolves about the axis of rotation of the bar 15 whereby partial rotation will be imparted successively to the shaft 28.

40 The operating string is tubular and continuing from its lower end down through the bar 15 there is a channel 32 whose lower end is outwardly turned through the side of said bar, and through which flushing fluid may be supplied to the milling tool during the sidetracking operations.

45 The lower end of the anchor 4 has a depending extension 33 which may be fastened to the upper end of the whipstock by means of a frangible pin or bolt 34.

50 The apparatus may be assembled as indicated in Figures 1 and 2 and let down into the well to the desired location and the whipstock may be set in the usual way. Thereupon, upon release of the weight of the operating string, the pin 34 will be sheared and the anchor will move on downwardly and wedge between the set whipstock and the surrounding casing or pipe in the manner indicated in Figure 4. However, at this time the milling tool 23 will be at the upper end of the bar 15 as indicated in Figure 2. The bar 15 will assume an

5 angular relation with respect to the axis of the pipe 1, the ball 8 pivoting on the key 9 to permit this. Upon rotation of the operating string 20 the milling tool 23 will be correspondingly rotated. With each rotation of the bar 15 the star wheel 30 will engage the finger 31 and be partly rotated, imparting a partial rotation to the feed shaft 28, thus gradually feeding the milling tool downwardly. The tool will be held in operating relation with the pipe to be perforated, and as it 10 moves downwardly, will mill an oblong "window" through the casing.

15 The milling tool 23 may also have a splined connection with the bar 15, if desired, as indicated in Figure 5.

20 Upon completion of the operation, the milling tool will have reached approximately to the lower end of the bar 15 and thereupon the entire apparatus may be withdrawn by means of the operating string 20 and further drilling operations may 25 be carried on through the perforation thus made in the side of the pipe 1.

25 The drawings and description disclose what is now considered to be a preferred form of the invention by way of illustration only, while the 25 broad principle of the invention will be defined by the appended claims.

What I claim is:

30 1. A sidetracking apparatus comprising an anchor adapted to be located between a whipstock in a well and the opposing side wall of the well and effective to prevent the turning movement of the whipstock in the well, a turnable bar whose lower end is connected with the anchor, a milling tool on and rotatable with the bar, means for feeding the tool downwardly as the bar rotates.

35 2. A sidetracking apparatus comprising an anchor adapted to be located between a whipstock in a well and the opposing side wall of the well, and effective to prevent the turning movement 40 of the whipstock in the well, a turnable bar whose lower end is connected with the anchor, a milling tool on and rotatable with the bar, means for feeding the tool downwardly as the bar rotates, and an operating string connected to and adapted to rotate the bar.

45 3. Apparatus of the character described comprising an anchor, a connection flexibly, but non-rotatably, connected with the anchor, a bar rotatably connected to said connection, means for 50 rotating the bar, a milling tool rotatable with the bar and means for feeding the tool along the bar as the bar rotates.

55 4. Apparatus of the character described comprising an anchor shaped to wedge between the sloping face of a whipstock and the opposing wall of a well in which the whipstock is located, a rotatable bar, one end of which has a connection with the anchor, a milling tool movable along the bar and rotatable therewith, an operating string 60 for rotating the bar, means for intermittently moving the tool along the bar as the bar rotates.

65 5. Apparatus of the character described comprising an anchor shaped to wedge between the sloping face of a whipstock and the opposing wall 65 of a well in which the whipstock is located, a rotatable bar, one end of which has a connection with the anchor, a milling tool movable along the bar and rotatable therewith, an operating string for rotating the bar, means for intermittently 70 moving the tool along the bar as the bar rotates to feed the tool to the work.

75 6. An apparatus for perforating pipe in a well comprising an anchor shaped to fit between a whipstock in the pipe and the opposite wall of 75

the pipe, a rotatable bar having connection with the anchor and in angular relation with the pipe, a milling tool on and rotatable with the bar, means for moving the tool along the bar and into working engagement with the pipe as the bar rotates.

7. An apparatus for perforating pipe in a well comprising an anchor shaped to wedge between a deflector in the pipe and the opposite wall of the pipe, a rotatable bar, means for connecting the bar to the anchor, said connecting means being flexibly connected to the anchor to permit the bar to assume an angular relation to the axis of the pipe to be perforated, a milling cutter on, and rotatable with, the bar, means for feeding

the cutter along the bar and into cutting relation as the bar rotates.

8. An apparatus for perforating pipe in a well comprising an anchor shaped to wedge between a deflector in the pipe and the opposite wall of the pipe, a rotatable bar, means for connecting the bar to the anchor, said connecting means being flexibly connected to the anchor to permit the bar to assume an angular relation to the axis of the pipe to be perforated, a milling cutter on, and rotatable with, the bar, means for feeding the cutter along the bar and into cutting relation as the bar rotates, and an operating string connected to, and effective to rotate, the bar.

ALBERT L. EASTHAM. 15
